DESIGN FOR A HUMIDIFIER

William A. Norris, Alhambra, Calif.

Application June 6, 1945, Serial No. 119,925

Term of patent 14 years

(Cl. D62—4)

To all whom it may concern:

Be it known that I, William A. Norris, a citizen of the United States, residing at Alhambra, in the county of Los Angeles and State of California, have invented a new, original, and ornamental Design for Humidifier, of which the following is a specification, reference being had to the accompanying drawing, forming a part thereof.

In the accompanying drawing:

Fig. 1 is a top plan view of a humidifier, showing my new design;

Fig. 2 is a side elevational view; and

Fig. 3 is a front elevational view thereof.

I claim:

The ornamental design for a humidifier, as shown.

WILLIAM A. NORRIS.
